Harry F. Curtis

By his Attorney

E. M. Marshall

UNITED STATES PATENT OFFICE.

HARRY F. CURTIS, OF OVERBROOK, PENNSYLVANIA.

CABLE-GRIPPING DEVICE.

Application filed February 11, 1921. Serial No. 444,122.

To all whom it may concern:

Be it known that I, HARRY F. CURTIS, a citizen of the United States, and a resident of Overbrook, county of Montgomery, 5 and State of Pennsylvania, have invented certain new and useful Improvements in Cable-Gripping Devices, of which the following is a specification.

This invention aims to provide a cable-gripping device which will permit a cable to be gripped at any point intermediate its ends for the purpose of enabling the same to be pulled by any suitable pulling means.

The invention has been embodied in a 15 structure comprising a shell and a wedge without any mechanical connections between them, the construction being such that the wedge and cable may be entered into and removed from the shell through a 20 slot in a wall of the same.

Other features of novelty and construction will become apparent from the detailed description of the invention taken in connection with the accompanying drawing 25 forming a part of this specification, reference, however, being had to the appended claims for the scope of the invention.

In the drawing wherein I have shown the preferred form of the invention, Fig. 1 30 is a side elevation of the clamping device showing a cable as gripped by the device.

Fig. 2 is a transverse section taken on the plane of line 2—2 of Fig. 1.

Fig. 3 is a side elevation showing the 35 wedge of the device in position to permit the cable to be entered into the shell.

Fig. 4 is a transverse section taken on the plane of line 4—4 of Fig. 3.

Fig. 5 is a side elevation of the device 40 showing how the members of the device may be held together when the device is not in use.

Fig. 6 is a side elevation of the device showing how the wedge may be entered 45 into or removed from the shell.

Fig. 7 is a cross section on the plane of line 7—7 of Fig. 6.

Like characters of reference indicate like 50 parts throughout the several views.

The invention has been embodied in a device in which one of the members is an open-sided shell S and the other is a plate-like wedge member W. The wedge proper is indicated at 10 and is shown as having a 55 restricted handle-like member 11 extending longitudinally thereof. The shell has a

taper corresponding to that of the wedge, the degree of taper being suitable for the purpose in view.

One wall of the shell or sleeve S is slotted 60 as at 12 to permit the cable C and wedge member W to pass therethrough. The extension 11 is preferably so arranged with respect to the wedge 10 that an edge 10^a of the latter shall be in the same plane as an 65 edge 11^a of the former. The opposite edges 10^b and 11^b are thus in stepped relation at point 13.

The terminal of the extension 11 is preferably in the nature of a lateral lug 14 of 70 substantial width to enable it to stand up under hammer blows to which it will be subjected in releasing the grip of the device on the cable and through this lug is passed a link or ring 15 to which may be attached 75 any suitable pulling device for drawing on the cable after it has been gripped.

The edge 11^b of the extension 11 is adapted to be entered through the slot 12 in the shell S, the length of the edge being at least 80 as long as the shell S, to permit such passage.

The relative position of the wedge and shell when brought to the cable is usually as indicated in Fig. 5.

When a cable is to be gripped, the shell is 85 moved longitudinally toward the small end of the wedge until the shoulder 13 is passed whereupon the shell is moved laterally of the wedge and seated on the shoulder 13. When the shell is heavy as is the case when 90 the device is constructed for use with large cables the advantage of so supporting the shell relatively to the wedge is obvious. The device is now in condition to receive the cable C, which as will now be readily seen, 95 may be gripped at any desired point since it is merely necessary to pass it through the slot 12.

After the cable has been entered into the shell the latter is pushed off the shoulder 13, 100 whereupon relative longitudinal movement of the shell and wedge will effect a gripping engagement with the cable which engagement is increased as the wedge is pulled in the direction of its small end as will be readily understood.

The cable-contacting edge 10^a of the wedge is preferably made slightly concave to center the cable on the wedge. The slot 12 is preferably though not necessarily of less width 110 than the width of the extension 11. When the slot is of less width the wedge member

is entered into or removed from the shell in the manner indicated in Figs. 6 and 7, that is to say, by passing the restricted part of the wedge member through the slot while 5 giving it a turning motion.

From the above it will be seen that I have provided an extremely simple and satisfactory cable gripping device. There are no mechanical connections between the wedge 10 member and sleeve and yet the arrangement is such that both members may be interlocked to prevent misplacement of the parts. The shell and wedge may be made from commercial plate material thereby making 15 for low cost of manufacture and by reason of the simple construction is not liable to get out of order.

While I have described the invention with great detail I desire it to be distinctly understood that I intend no limitations other than those imposed by the appended claims. 20

What I claim is:

1. In a cable gripping device, the combination of a tapered shell having a slot intermediate its tapered edges, a wedge member having a restricted portion greater in length than the length of said shell, the restricted portion being separated from the remaining

portion of the wedge member by a shoulder transverse to the wedge member whereby the 30 shell may be supported and rotated upon said shoulder.

2. A cable gripping device having in combination a flat wedge having an edge with a single sharply defined indentation forming 35 a transverse shoulder thereon and a shell having the same internal taper as the wedge and having a slot in one of its walls, the slot being of such width that the wedge may be removed from the shell by tilting and sliding the wedge on its transverse shoulder until one edge of the wedge projects through the slot.

3. In a cable gripping device, a tapered shell having a slot intermediate its tapered 45 edges, a wedge member having a straight edge and having a transverse shoulder opposite said straight edge, with the parts forming the other edge at substantially the same angularity to the straight edge, the 50 transverse shoulder serving as a support for the shell.

In witness whereof, I have hereunto set my hand this 10th day of February, 1921.

HARRY F. CURTIS.
